Jeremiah D. Green (assignee of Viell & Warren) Troy, New York,
Letters Patent (Design No. 156) dated Oct 2^d. 1847.

The schedule referred to in these Letters Patent and making
part of the same.

To all whom it may concern: Be it known that I, Jeremiah D. Green of Troy, in the County of Rensselaer and State of New York, have invented or produced a new and useful design for an ornamental Airtight Stove and I do hereby declare that the accompanying drawings are full and accurate representations of my said design, Fig. 1, being a perspective view of one of my stoves, to shew the general form, and Figs 2, 3, 4 & 5, being respectively the top, bottom, side and end plates upon a larger scale to shew the detail of ornament.

Dec 156

Fig 6. Exhibits the form and ornaments of the water vase which surrounds the stone, and Fig 7. those of the leg.

To save unnecessary labor in drawing, but half of the several plates, vase and leg are delineated, the remaining parts being similar to and symmetrical with those represented. But one quarter of the top is shown for the same reason. The borders indicated at $a a \times b b$ are continued around their respective panels.

What I claim as my invention and desire to secure by letters patent is the combination of ornamental forms and figures forming, the bottom, sides & end plates respectively and likewise those of the vase and leg, as shown in the accompanying drawings, - the whole forming a design for an Airtight Parlor Stone.
